UNITED STATES PATENT OFFICE.

WILLARD H. KEMPTON, OF WILKINSBURG, PENNSYLVANIA, ASSIGNOR TO WESTINGHOUSE ELECTRIC & MANUFACTURING COMPANY, A CORPORATION OF PENNSYLVANIA.

MOLDED COMMUTATOR-CYLINDER AND METHOD OF FORMING SAME.

1,326,349.

Specification of Letters Patent. Patented Dec. 30, 1919.

Application filed September 10, 1917. Serial No. 190,508.

To all whom it may concern:

Be it known that I, WILLARD H. KEMPTON, a citizen of the United States, and a resident of Wilkinsburg, in the county of 5 Allegheny and State of Pennsylvania, have invented a new and useful Improvement in Molded Commutator-Cylinders and Methods of Forming Same, of which the following is a specification.

10 My invention relates to commutator cylinders and particularly to commutator cylinders in which the assembled conducting and insulating sections are held in position by molded insulating material.

15 In my Patent No. 1,284,362, dated Nov. 12, 1918, is shown a commutator cylinder that is formed by assembling alternate conducting and insulating sections and then applying an insulating material by means 20 of a suitable mold to hold them in their proper positions. The insulating material is preferably bakelite that is applied in a plastic condition, and it has been found that as the particles of insulating material 25 move over the surfaces of the conducting sections, under the influence of heat and pressure, minute flakes of copper are sometimes removed from the surfaces of the bars on account of the scouring action of the insulating material. These flakes of copper 30 are liable to cause short circuits between adjacent conducting sections.

By my invention, I provide means for protecting the surfaces of the conducting 35 sections against the above described scouring action.

In the single figure of the accompanying drawing, alternate conducting and insulating sections 1 and 2, respectively, are shown 40 arranged in annular form with portions thereof, embedded in molded insulating material 3 that is supported upon a hollow cylindrical sleeve 4 by means of which the commutator cylinder is attached to a shaft, 45 (not shown). Each conducting section is provided with a dried protective coating 5 of enamel or some other suitable insulating material over those portions of its surfaces which the molded insulating material 50 engages. The protective coating may be applied by dipping each section or by applying the coating to the exposed surfaces of the assembled sections. The coating prevents the insulating material which passes

over the cylinder, under the influence of 55 heat and pressure, from coming into contact with the conducting portions and thus prevents any flakes of copper from being removed by the scouring action. In this way, the possibility of short circuits occurring 60 between the conducting sections is substantially eliminated.

While I have shown my invention as applied to conducting sections of commutator cylinders, it will be understood by those 65 skilled in the art that it is not so limited, but may be applied to a conductor or other body which is subject to having molded insulating material pass over it, and I desire, therefore, that only such limitations shall 70 be placed thereupon as are imposed by the prior art or are specifically set forth in the appended claims.

I claim as my invention:

1. A conducting member embedded in 75 molded insulating material and having its embedded portion provided with a protective coating.

2. A commutator bar embedded in molded insulating material and having its embedded 80 portion provided with a coat of enamel.

3. A conducting member embedded in molded insulating material which has been hardened under the application of heat and pressure, the embedded portion of the conducting member being provided with a protective coating. 85

4. A conducting member embedded in a phenolic condensation product which has been hardened by the application of heat 90 and pressure, the embedded portion of the conducting member being provided with a protective coating of enamel.

5. The method of molding composite bodies of insulating material with inserts of 95 conducting material which comprises providing the inserts with a protective coating, embedding them in the insulating material and molding the body thus assembled.

6. The method of molding composite bodies of an insulating material which will harden under the application of heat and pressure with inserts of conducting material which comprises providing the inserts with a protective coating, embedding them in the material and molding the body thus assembled by application of heat and pressure. 105

7. The method of molding composite

bodies of a phenolic condensation product and metallic inserts which comprises providing the surface of the inserts with a protective coating of enamel, drying the coating, 5 embedding the inserts in the phenolic condensation product and hardening the phenolic condensation product by the application of heat and pressure.

8. The method of forming a commutator 10 in which commutator bars are embedded in an insulating material which hardens under the application of heat and pressure which comprises providing the surfaces of the bars with a protective coating, embedding 15 the bars in the insulating material and sub-

jecting the body thus assembled to heat and pressure to harden the insulating material.

9. The method of forming commutators in which commutator bars are embedded in a body comprising a phenolic condensation product which comprises coating the commutator bars with an enamel, drying the enamel, properly disposing the bars in the insulating material and subjecting the body thus assembled to heat and pressure to 25 harden the insulating material.

In testimony whereof, I have hereunto subscribed my name this 20th day of August, 1917.

WILLARD H. KEMPTON.
